UNITED STATES PATENT OFFICE

164,734

CUBICLE PARTITION UNIT

Edward F. Quinn, Larchmont, N. Y., assignor to
the United States of America as represented by
the Secretary of the Army

Application May 16, 1950, Serial No. 9,966

Term of patent 3½ years

(Cl. D33—1)

To all whom it may concern:

Be it known that I, Edward F. Quinn, a citizen of the United States, residing at Larchmont, in the county of Westchester and State of New York, have invented a new, original, and ornamental Design for a Cubicle Partition Unit of which the following is a specification, reference being had to the accompanying drawings, forming a part thereof.

Fig. 1 is a perspective view of a cubicle partition unit, showing my new design with one of the lockers open;

Fig. 2 is a plan view thereof; and

Fig. 3 is a front elevational view thereof.

The dominant features of the design are shown in full lines.

I claim:

The ornamental design for a cubicle partition unit, substantially as shown and described.

EDWARD F. QUINN.
